UNITED STATES PATENT OFFICE.

JAMES M. NAUL, OF PLAINFIELD, NEW JERSEY, ASSIGNOR, BY MESNE ASSIGNMENTS, TO AMERICAN BOSCH MAGNETO CORPORATION, OF NEW YORK, N. Y., A CORPORATION OF NEW YORK.

ELECTRIC SWITCH.

1,320,704.

Specification of Letters Patent.

Patented Nov. 4, 1919.

Application filed March 10, 1916. Serial No. 83,371.

To all whom it may concern:

Be it known that I, JAMES M. NAUL, a citizen of the United States, residing at and whose post-office address is 655 East Seventh 5 street, Plainfield, county of Union, State of New Jersey, have invented certain new and useful Improvements in Electric Switches; and I do hereby declare the following to be a full, clear, and exact description of the invention, such as will enable others skilled in the art to which it appertains to make and use the same.

The prior art contains electric switches having a key which may lock the switch 15 against movement at any position to which it is set, and which may be removed to prevent unauthorized movement of the switch from the set position. Such switches have an "off" position at which some of the circuits controlled thereby are interrupted and some are grounded, and also one or more operative positions at which the several circuits are individually or collectively closed, so that grounding or closing a certain circuit necessitates a certain connection for some or all of the other circuits. For instance, in the well known form of combined lighting and ignition switch for automobiles, motor boats and the like, all the lighting 20 circuits must be interrupted to ground the magneto at the off position, and if some of the lights are to be left burning the magneto cannot be grounded by the switch. This arrangement is unsatisfactory because the operator often wants to leave the moving vehicle at rest with some lights burning and yet desires to lock the magneto in a grounded position to prevent unauthorized operation of the engine. Furthermore, the operator 25 may want to stop the engine by grounding the magneto and yet the lights should not be extinguished.

The switch herein disclosed is adapted to control a plurality of circuits, but it overcomes the disadvantages of the switch hereinbefore referred to by providing a supplementary contact which is engaged in removing the key from its normal position in order to lock the switch in set position. In using this switch to control lighting and ignition circuits, the insulated electrode of the mechanical interrupter of the magneto is connected to the supplementary contact and that contact is grounded when the key 30 is being removed, irrespective of the position

in which the switch is locked. In the preferred form of switch for this purpose, the insulated electrode is also connected to another contact which is grounded when the switch is in the off position, irrespective of the position of the key. Thus the magneto may be short-circuited by turning the switch to off position as heretofore, and also the magneto may be short-circuited to prevent unauthorized operation of the engine by removing the key to lock the switch, irrespective of whether lights are burning or are extinguished. Furthermore, by bringing about the engagement of the supplementary contact during rotation of the key to its position of removal, the magneto may be short-circuited merely by turning the key in the lock. I prefer to do this because the operator sometimes wants to shut off the ignition when going along, while at the same time he does not want to extinguish the lights and does not need to remove the key.

In the accompanying drawings illustrating the preferred form of switch in application, as an example, to lighting and ignition circuits, Figure 1 is a front view of the switch in off position, the key being removed; Fig. 2 is a section through the switch; Fig. 3 is a rear view of the front part of the switch; Fig. 4 is a front view of the rear part of the switch; and Figs. 5 and 6 are enlarged detail views showing the supplementary switch in closed and open position, respectively.

The switch has a cup-shaped casing 4 of metal with a flange 5 adapted to be screwed to a support. The base block 6 of the insulating material is fastened to the casing by screws and forms therewith an inclosed cavity for the reception of the operating parts of the switch, as will appear hereinafter. The operating handle 7 carries a spindle 8 journaled centrally in the casing as shown and riveted to the lock plate 9, these parts being arranged to turn between the limits determined by the terminal faces of the boss 10. Six circuit contacts 11, 11' and 11'' of copper in the form of slotted studs are held rigidly in the base block and are engaged by binding post screws to which circuit wires may be attached at the back. The central hollow stud 12 of copper has a connecting screw 13, and provides at its inner end a journal on which the switch arm can turn. The end of the journal is forced

back against the copper washer 15 after the switch arm is in place on the journal and forms a good electrical connection between the parts. The switch arm is made up of two 5 copper segments 16 spaced apart by the metal washer 17 and having opposite flanges of different extent. The ring 18 of insulating material is riveted to the switch arm and is provided with two holes 19 into which project two pins 20 from the rotatable lock 10 plate 9. The slots in the two studs 11' and 11'' are higher than those in the other studs 11, and the two segments 16 are spaced apart to such extent that the studs 11' and 11'' 15 are not engaged whereas the studs 11 are engaged when the switch arm is moved past them upon turning the handle 7. A bent copper strip 21 carried on the pins 20 and pressed against the ring 18 by an arched 20 spring 22 passes over the studs 11, but engages the top of the stud 11'', which is longer than the studs 11, to ground it on the metal part of the casing when the switch is turned to off position.

25 The locking mechanism comprises a member 23 held in place in a cavity of the casing 4 by the pin 24 which projects from the casing almost but not quite to the center of rotation of the member 23, and a key 25 30 which can be inserted in place and withdrawn therefrom only in that position wherein a peripheral part 23^a of the member sets in a peripheral recess of the lock plate 9. In this position the lock plate cannot be 35 turned from its set position, irrespective of what position that may be, but when the peripheral part 23^a is turned by the key 25 somewhat less than 180°, in which position the key can not be removed, the lock plate 40 may be turned without interference by the peripheral part 23^a of the member 23, since that part is then out of registry with the lock plate. A copper strip 26 is mounted directly underneath the member 23 and is so 45 shaped that when the peripheral part 23^a is disengaged from the lock plate, the spring 27 forces the strip 26 out of engagement with the stud 11', and when the member 23 is turned so that the peripheral part thereof 50 engages the lock plate, the strip is forced by the upper face 23^b of the member 23 into engagement with the stud 11' to ground that stud on the casing. The two studs 11' and 11'' 55 are electrically connected by a wire 28 and the strip 26 forms in effect a switch blade guided in its movement to and from the stud 11' by the pin 29.

The switch herein shown has four positions designated on the front of its casing by 60 0, 1, 2, 3, the position 0 being the off position in which the strip 21 engages the stud 11'' to ground it and in which the segments 16 are disengaged from all the studs. In the position marked 1, as shown in Figs. 2 and 65 4, the wide flanges of the segments 16 engage

one of the studs 11 to connect it to the screw 13. In the position marked 2, the two studs 11 on one side are engaged by the wider flanges of the segments, and one stud 11 on the other side is engaged by the narrow segments. In the position marked 3, the same two studs 11 are engaged by the wider flange, and the other stud 11 on the other side is engaged by the narrow flanges. The stud 11'' is intended to be electrically connected to the insulated electrode of the mechanical interrupter of the magneto, so that when the switch is turned to its off position, or when the key 25 is turned to the position in which it may be removed from the key-hole and in which the switch is locked against movement, the magneto is short-circuited and discontinues the generation of ignition voltages. The spring pressed ball 30 snaps into a recess of the lock plate 9 at 85 each one of its four positions to lightly hold the switch in that position.

It is apparent that the idea herein disclosed of engaging a supplementary contact or closing a supplementary switch in removing the key to lock the switch in set position may be applied to various forms of switches for controlling various kinds of circuits.

Having thus described my invention, what I claim is:

1. In an electric switch, a plurality of circuit contacts, a switch arm engageable successively with some of said circuit contacts, a supplementary contact electrically connected to another of said circuit contacts, a grounded member carried by said switch arm and movable into engagement with said supplementary contact at one position of the switch arm, and mechanism constructed and arranged to lock said switch arm in any of its successive positions and to simultaneously ground said supplementary contact.

2. In an electric switch, a plurality of circuit contacts, a switch arm engageable successively with some of said circuit contacts, a supplementary contact electrically connected to another of said circuit contacts, a grounded member carried by said switch arm and movable into engagement with said supplementary contact at one position of the switch arm, and mechanism including a removable key, which upon being turned to the position in which it may be removed, locks said switch arm in any of its successive positions and simultaneously grounds said supplementary contact.

3. In an electric switch, a plurality of circuit contacts, a switch-arm engageable successively with some of said contacts, a grounded member on the switch-arm, an additional contact adapted to be engaged by said grounded member in one position of the switch-arm, a second additional contact and mechanism constructed and arranged to

lock said switch-arm in any of its successive positions and to simultaneously ground said second additional contact.

4. In an electric switch, a plurality of 5 circuit contacts, a switch arm engageable with said contacts in succession, a supplementary switch, and locking mechanism including a plate rotatable with the switch arm, a removable key and a key-operated 10 member which, upon being turned to a position in which the key may be removed, locks said plate against movement at any of its successive positions and also closes said supplementary switch.

15 5. In an electric switch, a rotatable switch shaft adapted to be set to various positions, a plate fixed on said switch shaft, a supplementary switch, and a key-operated member having two actuating parts which, in the 20 position of the member wherein release of the key is permitted, lock said plate in any of its set positions and close said supplementary switch, and which, in the position of the member wherein release of the key is

precluded, release said plate and open said 25 supplementary switch.

6. An electric switch comprising the combination of a plurality of contacts, a rotatable switch-arm adapted to be moved into and out of engagement with said contacts, 30 a supplementary contact, a grounded member carried by the switch-arm and engaging the supplementary contact in one position of the switch-arm, a second switch-arm, 35 a contact with which the second switch-arm coöperates, a key-operated rotatable locking device for holding the first switch-arm against movement, means for operating the second switch arm by rotation of the locking device to locking position, and means 40 for sustaining a key in position for operating said rotatable locking device and for precluding removal of the key except when the locking device is in locking position. 45

In testimony whereof I affix my signature.

JAMES M. NAUL.
